UNITED STATES PATENT OFFICE.

HENRY STANLEY AND REUBEN COMINS, OF TROY, NEW YORK.

IMPROVEMENT IN FASTENING TIMBERS.

Specification forming part of Letters Patent No. 43,718, dated August 2, 1864.

To all whom it may concern:

Be it known that we, HENRY STANLEY and REUBEN COMINS, both of the city of Troy, in the county of Rensselaer and State of New York, have invented a new and improved mode of fastening timbers and other material together longitudinally by use of metallic clamps or other material, either alone or combined, to prevent their separating or pulling asunder when subject to tensile or transverse strain, or both, which is usually known and termed "splicing;" and we hereby declare the following to be a full and exact description thereof, reference being had to the accompanying drawings, making a part of this specification, in which—

Figure 1 is a longitudinal elevation. The rest of the figures are sections of Fig. 1, showing parts of it on an enlarged scale, Fig. 2 being a longitudinal elevation of a section containing splicing and clamp; Fig. 3, a plan of same; Fig. 4, a diagonal cross-section on $x'x$ in Fig. 2; Fig. 5, a cross-section through joint $a'a'$ in Figs. 2 and 3. Fig. 6 is another longitudinal elevation of a section of splicing and clamp differing slightly in detail from Figs. 2, 3, 4, and 5, but the same in principle and operation; Fig. 7, a plan of one side; Fig. 8, a plan of opposite side to Fig. 7; Fig. 9, a diagonal cross-section on line $y'y$ in Fig. 6, and Fig. 10 a cross-section through joint $d'd'$ in Figs. 6 and 7. Figs. 11 and 12 will be herein subsequently referred to and explained.

Like letters of reference marked on the drawings indicate corresponding parts in Figs. 1, 2, 3, 4, 5, 11, and 12, also in Figs. 6, 7, 8, 9, and 10.

Parts indicated by letters will first be explained in Figs. 2, 3, 4, and 5, and are as follows: letters A, timbers or pieces spliced and clamped; B, bands or clasps to clamps; C, screw-bolts or ties; D, saddles or bearing-pieces, and E saddles and straining-blocks. In Figs. 6, 7, 8, 9, and 10, letters F, timbers or parts of material joined or spliced; H, clasps or yokes; I, saddles and straining-blocks, and L tie-plate or ties. But one name will be used to each of the foregoing parts in this description hereinafter.

This invention relates particularly to splicing bottom chords to truss-bridges, tie-beams to truss-roofs, and to truss-frames generally

where more than one piece in length are required to form the tie part or chords, and for all purposes where it is desired to resist tension by use of two or more pieces in length; also to strengthening beams and of forming them of two pieces abutted together endwise, using the clamps at the joints, being applicable and useful in all cases to increase their strength and rigidity transversely.

To enable others skilled in the art to make and use our invention, we will proceed to describe its construction and operation.

The timbers or parts to be spliced may be of any desirable dimensions abutted squarely together endwise, as seen at $a'a'$ in Figs. 2 and 3, and at $d'd'$ in Figs. 6 and 7, making a close or open joint, as may be desirable. A straining-block is placed each side of the joint $a'a'$, at a short distance from it, and connected with screw-bolts or ties. Upon the opposite side from the straining-blocks, and a little farther back from the joint than said blocks, a saddle is put, and around these saddles and blocks the bands pass, connecting them by surrounding or encompassing them and timbers. This constitutes a single clamp, and the same operation repeated from opposite sides a double one, as seen in Figs. 1, 2, and 3. The straining-blocks and saddles should be so arranged and placed that the bands that surround them will pass from one to the other, crossing the timbers or parts joined and spliced diagonally, forming an angle of about forty-five degrees, (more or less,) and that part of their surface which comes in contact with the bands as they pass around them should be so formed as to receive them with a natural and easy bend, so as to not impair their strength, and also to keep them in their places on the desired angle; and their opposite surface or sides, which come in contact with and rest upon the pieces spliced, should be made to fit and adhere snugly to them with sufficient bearing-surface to prevent its crushing the material upon which it rests, and the straining-blocks should have holes or recesses in them for the ties that connect them, having a proper bearing for the nuts $e'e'$ to rest against. Bands may be flat, round, or of any other convenient form, and should be so bent and welded or fastened together as to form a link or clasp that will surround the timbers,

straining-blocks, and saddles, as hereinbefore described, fitting them easily and snugly, or that part of their surface designed to receive and hold them in their places, forming the requisite angle. The tie-rods may be round, flat, or of any other form desirable, made to pass through the holes in the straining-blocks, with screw and nut $e' e'$ on each end or upon one end only, with a head at the other, as may be most convenient and desirable, and one or more of these ties may be used to each clamp, as may be deemed proper. Thus it will be seen that two straining-blocks, two saddles, two clasps or bands, and a tie form a clamp which may be used doubly or singly. Its operation is twofold, a desired effect being produced by two different methods. First, by turning up the nuts $e' e'$ to the ties, causing a strain to be produced upon them which will bring the whole clamp into effectual operation, thus causing all its parts to act, and by this means it will grip the parts to be held together, having a tendency to draw them nearer each other to any desired position, and there hold them, and the greater the strain put upon the ties by means of the nuts the firmer the grip, making the clamp more effectual. After having the clamp placed and adjusted, and joint regulated at will, as just described, the second method of operation is by applying tensile strain to the parts spliced, which will also cause a gripping, the same as in the first method, and the greater this force the more effectual is the operation of the clamp in service, and as it increases the clamp will correspondingly clasp the parts joined or spliced, thereby grasping and adhering to them more firmly, thus securing and holding them more tenaciously in their proper places, and all parts of the clamp, or, in other words, the greater the tension the more powerful and effectual the grip and clamp—an operation believed to be produced by no other arrangement; and it also operates to increase the strength of beams and to admit of their being spliced or made of two parts abutted together endwise when subject to transverse strain, as herein elsewhere explained.

We sometimes construct our splice and clamp as seen in Figs. 6, 7, 8, 9, and 10, being the same in operation, principle, and effect as in the other case, differing only slightly mechanically in some of its details, which are equivalent in their construction, application, and use. Instead of screw-bolts or ties with nuts across joint $d' d'$, we use a tie-plate, L L, with shoulders near each end to receive and hold the clasps H H upon one side of pieces, F F. The clasps are bent in the middle to pass around tie-plates against the shoulders of them and outside of the timbers, crossing them diagonally to straining-blocks I I on opposite side to plates through which they pass, having nuts $g g$ to take hold of them, so the tightening of the clamp and drawing joint together is performed from nuts on the diagonal

parts or clasps rather than from nuts upon longitudinal parts or tie, as in Figs. 2 and 3. This arrangement may be used double or single, clasps flat or round, as seen in Figs. 6, 7, and 8, or any other convenient form; and so with the tie part or plate. In some cases the diagonal parts may be made to pass through parts spliced, instead of around them, taking hold of tie or plate in any effective manner, and saddles or bearing-pieces on opposite side by means of nuts or similar device.

The saddles and straining-blocks may be made with spurs or ledges, or both, as seen in Figs. 11 and 12, rendering them less liable to move, and in some cases may be slightly inserted into the parts spliced without materially diminishing their strength or tensile power; but this will be found unnecessary when bands and clasps are placed on a proper angle, as then they will not slide or move, but, on the contrary, remain more securely and safely in their respective positions as the tensile force is applied and increased. Any desired angle may be used, but a few degrees less than forty-five may be found most effectual and useful. The cross-section of the clamp, subject to tension when only one is used, should be equivalent in strength to that of the available cross-section of parts spliced, taking into consideration the material used in both cases, in order to make the splice as strong as elsewhere, thereby securing the entire tensile capacity of all the material used, which we believe is not accomplished by any other arrangement in use or known, nor very nearly so. When applied double, one-half the cross-section will be required in each clamp that would be requisite if single.

It may be obvious to any one skilled in the business that this mode of joining material and applying clamps—or, in other words, splicing it—is simple and economical. The joint and splice is easily and cheaply made, requiring less material than where laps are used; and in cases abutted together, as in this, with wood or metal clamps adopted, the pieces joined are very materially reduced in size or cut away in their cross section to receive the clamp, or for the purpose of attaching it to them, thereby decreasing their tensile power correspondingly, causing serious loss in strength or of material, or both, which is entirely obviated and avoided by this plan and operation, securing substantially all the strength of the material used—or, in other words, preserve its entire cross-section when necessary—making it all available for the purposes for which it is required, and will be as strong at the joint and all parts of the splice as elsewhere, if the clamp is properly proportioned and applied; also, it lessens the liability of the timber to decay, as it has no place to receive and hold water or moisture, being cut in no manner for the clamp, which in other plans is a serious matter, while the clamp itself is simple, easily, quickly, and

cheaply made and applied, all of which may be seen to be of great importance and serious consideration.

What we claim as our invention and improvements in the mode of joining or fastening timbers longitudinally to prevent their separation, and desire to secure by Letters Patent, is—

A clamp constructed and combined with

the timbers to be joined in the manner substantially as and for the purposes herein described and set forth.

HENRY STANLEY.
REUBEN COMINS.
